UNITED STATES PATENT OFFICE.

BENJAMIN C. VANDUZEN, OF WINTON PLACE, OHIO, ASSIGNOR, BY DIRECT AND MESNE ASSIGNMENTS, TO THE VANDUZEN GAS AND GASOLINE ENGINE COMPANY, OF CINCINNATI, OHIO.

GAS-ENGINE.

SPECIFICATION forming part of Letters Patent No. 600,754, dated March 15, 1898.

Application filed June 15, 1891. Serial No. 396,404. (No model.)

To all whom it may concern:

Be it known that I, BENJAMIN C. VANDUZEN, a citizen of the United States of America, and a resident of the town of Winton Place, in the county of Hamilton and State of Ohio, have invented certain new and useful Improvements in Gas-Engines, of which the following is a specification.

The several features of my invention and the various advantages resulting from their use conjointly or otherwise will be apparent from the following description and claims.

In the accompanying drawings, making a part of this specification and to which reference is hereby made, Figure 1 is a side elevation of an engine combined with carriage embodying my invention. The fly-wheel of the engine and those wheels of the carriage which are at the side of the vehicle nearest the spectator are omitted in order to better exhibit the mechanism which is next behind them. Fig. 2 is a general plan of the engine and carriage as seen when the roof has been removed. Fig. 3 is a transverse section of the carriage, taken in the plane of the dotted line 3 3 of Fig. 1 and showing that face or side of the section which faces toward the left in Fig. 1, the engine being shown in front elevation. This figure is shown on a larger scale than Figs. 1 or 2. Fig. 4 represents a side elevation of a portion only of the engine, the view being taken from the same point as that shown in Fig. 1. This view shows in vertical central section the shell of the receiving-valve for receiving the gasoline and the shell of the lighter-valve, other parts of the said valve and the valve-gear being shown in section. Fig. 5 is a sectional view of the gas-cylinder and its jacket and the water-space between the two, the section being taken in the plane of the dotted line 5 5 of Fig. 4 and that face of the section being shown which faces upward in Fig. 4. This figure also shows in plan the bottom flanges of the cylinder-jackets and the bolt-heads and bolts connecting it to the uprights, whereby the cylinder and jacket are preferably supported. Fig. 6 is a horizontal section of the said shell of the gasoline-receiving valve and of the shell of the

lighter-valve and showing the top of the receiving-valve and a section of the lighter-valve, the section being taken in the plane of the dotted line 6 6 of Fig. 4, the heads of the bolts for securing the valve to the cylinder-head being omitted. Fig. 7 is a plan view, showing the chimney, the carbureter-valve, and the valve-stem and the connections to cover of valve C² and showing the tube D⁹ with the ball D¹² removed. Fig. 8 is a vertical section of the double receiving-valve adapted to receive either gas or gasoline and of the igniter-valve, this section being taken in the plane of the dotted line 8 8 of Fig. 8². Fig. 8' is a horizontal section of the said double receiving-valve, the said section being taken in the plane of the dotted line 8' 8' of Fig. 9, a section of the igniter-valve being omitted. Fig. 8² is a horizontal section of the double receiving-valve and igniter-valve, taken in the plane of the dotted line 8² 8² of Fig. 8, that face of the section being shown which faces toward the left hand in Fig. 8, the valve proper being shown in elevation. Fig. 9 is an elevation of that side of the said double receiving-valve which is on the left hand in Fig. 8. Fig. 9' is a top view of the said double receiving-valve shown in Fig. 9. Fig. 9² is a bottom view of the said double receiving-valve shown in Fig. 9. Fig. 10 is a vertical central section of the receiving-valve and of its connecting parts, the valve proper being shown in elevation. Fig. 11 is an edge elevation of the same. The spring D¹⁵ and the extension of the rod which accompanies it is omitted in order to better disclose those parts directly back of them and which would not otherwise be seen in this view. Grouped with this Fig. 11 and located at the lower right corner thereof is an edge view of the bracket and rod D¹⁴, both bracket and rod being broken off, as shown.

A indicates a jacket or shell surrounding the cylinder B of the engine. (See Figs. 1, 3, and 4 and more particularly Fig. 5.) Between the jacket A and the cylinder B is a space A', in which water is present, either still or, as will preferably be the case in most instances, flowing through the said space. This

water aids in keeping the cylinder cool for preventing the oil lubricating the piston and the interior of the cylinder from being burned.

B' indicates the cylinder-head. (See Figs. 5 and 4.)

F⁵ is a crank-shaft provided with a double crank F², journaled as hereinabove mentioned. To the wrist of this crank is connected the lower or outer end of the pitman B², the upper end of the pitman being in any suitable manner connected to the piston-rod of the cylinder B. The piston and piston-rod and upper end of the said rod may be of any well-known construction, and a drawing of the same has consequently been omitted. They form no part of the present invention.

C indicates a suitable carbureter. Gasoline enters this carbureter through the conduit R¹⁰, and air entering the carbureter through an appropriate conduit or opening is carbureted in the said carbureter. The carbureted air thence passes through. A valve C², connected to the carbureter by a suitable passage, as C', controls the admission of carbureted air from the carbureter to the cylinder B. The mode in which this valve is operated will be hereinabove explained. The carbureted air after passing valve C² enters the cylinder through passage-way C³ (see Fig. 4) into the cylinder.

An igniter apparatus is present, and a preferred kind thereof is the one shown. In this apparatus D indicates the valve, reciprocating through the tube D'. In the side of the tube is a conduit D², connecting the conduit or space C³ with the interior of said tube. Above the upper end of the tube is an opening D³, into which a flame from the igniter-burner D⁴ enters, the amount of fuel supplied to the burner being regulated by a suitable valve—viz., as screw-valve D⁵. In the present instance the fuel supplied to the burner is gasoline and is supplied to the valve by the pipe D⁶. The igniter apparatus is supplied with a chimney, as E', for conveying away the volatile products of combustion from this burner and at the same time bringing them into close contact with the tube D⁹ for keeping the latter at a high temperature.

When gas is ignited in the space D¹⁰ by the red-hot pipe D⁹, the volatile products of combustion generated therein escape through said pipe and through the hollow sphere D¹² at the top of pipe D⁹, the said sphere having an opening D¹³ in its top, through which said volatile products of combustion escape. Further description of the carbureter and igniter is herein deemed unnecessary, as their specific construction forms no part of the present invention. The form of carbureter and igniter here indicated is taken from those specifically set forth in the Letters Patent of the United States No. 448,386 and dated March 17, 1891, and should details of their construction be desired reference is hereby respectfully made thereto. On the other side of the cylinder is the exhaust-valve E, pref-

erably arranged, as shown, to exhaust during every fourth stroke of the piston.

The construction of the exhaust-valve is 70 preferably similar to that of the valve C²; but no one particular construction is essential over another. The particular construction of the valve forms no feature of my invention.

F indicates the cam-shaft, journaled in journal-bearings F' F', supported by the front up- 75 rights or posts K', which latter uphold the cyl-

inder. At the outer side of each journal-bearing F' the cam-shaft projects and carries a crank F³. One of these cranks F³ recipro-

cates a pitman F⁴, moving one end of a lever F¹¹, whose other end is pivoted at F¹². A re-

ciprocating stud F⁷ on this lever at each up- 80ward movement carries the valve-rod F⁸ up-

ward and lifts and opens the exhaust-valve, 85 and spring F⁹ aids in returning the said valve to its seat as the stud F⁷ descends. The other

of these cranks F³—viz., the one seen in Fig. 1 and also seen on the right-hand side in Fig.

3—is connected to one end of the pitman G. 90 The other end of the said pitman is connected

to a lever G', and the latter is at one end pivoted to a support—viz., at G². The free

end of said lever carries the stud G³. (See

Fig. 3.) The valve-stem C⁴ at its outer end 95 is connected by pivot C⁵ to a rod C⁶. The

lower end of the latter is adjustable in a re-

ciprocating curved path of which the pivot at

its outer end is the center. This rod C⁶ is 100 connected to the governor H in substantially

the following manner: One end of a rod J is

pivoted at J¹ to the reciprocating rod C⁶. The

other end of the rod J is pivoted at J² to the

lever J², pivotally fulcrumed on a pivot J³.

The other end of this lever J² is pivotally con-

nected at J⁴ to the lever J⁵, reciprocated by a

governor H. The governor H may be one of

the well-known forms, one description of

which is indicated in the drawings. The

means whereby the governor reciprocates a 110

lever, as J⁵, is also well known, and further

description of the governor and lever is there-

fore herefrom omitted.

Rotary motion is communicated to the gov-

ernor from the engine in any suitable man-

ner. In the present illustrative instance the

governor is provided with the gear-wheel H³,

which meshes with the gear-wheel H², in turn

meshing with the gear-wheel H' on the crank-

shaft F⁵. The operation of this portion of

my device is as follows: The crank-shaft F⁵

is rotated through the agency of the pitman,

piston-rod connected directly to said pitman,

and the piston of the cylinder. It recipro-

cates the pitman through the intermediate 125

gears H', H², and H³, and thereby recipro-

cates the free end of the lever G'. When the

engine is running at its regular speed, the

governor will be in such a position as that,

through the agency of the rods J² and J, it

will hold the free end of the reciprocatory

rod C⁶ directly opposite and in the path of

the stud G³ of the lever G', and consequently

further forward movement of the lever G'

will bring the stud G³ against the end of the rod C⁶ and move the latter forward, and thus move the valve C² off of its seat and allow a new charge of gas to enter the cylinder. As 5 the lever G' is retracted the spring C⁷, pressed substantially as shown, operates to draw the valve C² back upon its seat and prevents the further ingress of carbureted air or gas into the cylinder. The rod C⁴ has a sleeve, and a 10 detent moving in a slot thereof.

The stud G³ is shown in Fig. 3 and is shown in dotted lines behind the lever G' in Fig. 4.

When the speed of the engine goes beyond its regular rate, the governor moves the rod 15 J⁵ and thereby through the agency of the intervening rod mechanism aforementioned moves the free end of the reciprocating rod C⁶ out of the path of the stud G³. When the rod C⁶ has assumed this latter position, the 20 reciprocating movement of the lever G' will not operate to open the valve C², because its stud G³ will pass by the end of the rod C⁶ without striking it, and consequently the valve C² will not be opened, and the engine 25 will not receive an additional charge of gas, and consequently the speed of the engine will gradually diminish until it reaches its regular rate of speed, at which time the governor will again place the rod C⁶ in position to be 30 again operated upon by the stud G³ of the lever G'. The lever G' is also used to operate the lighter by the following means of my invention:

A curved arm G⁴ is fixed to and reciprocates 35 with the lever G'. The upper end of this arm G⁴ is provided with the projection or lug G⁵. A shaft D¹⁴, connected to the valve D of the lighter, extends downward and is at its lower end set by a fixed stud D¹⁶, through 40 which latter it reciprocates. On this rod D¹⁴ is fixed a projection D¹⁷. This projection is preferably constructed so that it can be fixed at any desired point upon the rod D¹⁴. The preferred mode of thus enabling it to be adjusted 45 consists in providing the projection with a set-screw D¹⁸, the projection D¹⁷ being in the shape of a sleeve and being capable of being slid on the rod D¹⁴. When the said sleeve has been located at the desired point 50 at D¹⁴, it is fixedly set there by means of a screw D¹⁸. The object of thus being able to set the projection D¹⁷ at the desired point on the shaft D¹⁴ is to adjust the distance between it and the hook of the lever, so that the lever 55 shall cause the igniter-rod D¹⁴ and valve D to reciprocate the desired distance. The spring D¹⁵ is located around the shaft D¹⁴ and compressed between the projection D¹⁷ and the fixed stud D¹⁶. Each backward movement 60 of the lever G' brings the hook G⁵ against the projection D¹⁷ and moves the igniter-valve backward, so that the gas in the passage-way or conduit C⁸ instantly enters the space within the shell of the igniter-valve and coming 65 into contact with the red-hot pipe D⁹ is ignited and simultaneously ignites the charge of gas in the passage-way C⁸ and in the cyl-

inder, thereby causing the piston rapidly to move downwardly and rotate the crank-shaft of the engine. As the lever G' moves forward the hook G⁵ leaves the projection D¹⁷, and the spring D¹⁵, heretofore compressed by the action of the hook G⁵ against the projection D¹⁷, is free to act and advances the projection D¹⁷, and with it the rod D¹⁴ and valve D, forward and shuts the igniter-valve, thereby cutting off all communication between the lighter and the passage-way C⁸. 70

The construction and purpose of the lever D¹⁹ are as follows: The collar D²¹ is fixedly attached to the lower end of the valve-rod D¹⁴. The lever D¹⁹ is pivoted to the stud D¹⁶, and when the engine is first started in operation the lever D¹⁹ is left out of contact with the collar D²¹ and the valve D and is free to be 80 operated by the hook projection G⁵. When the engine is running quite rapidly, then the gas in the cylinder is not ignited by the igniting apparatus with sufficient rapidity and the valve C² is held back, so as to leave the 85 opening between the passage-way C⁸ and the red-hot pipe free and uninterrupted. To accomplish this purpose, I move the lever D¹⁹ between the collar D²¹ and D¹⁶, thereby removing the said valve from the path of the 90 gas passing over the chamber C⁸ to the red-hot pipe D⁹. 95

The main crank-shaft F⁵ may be provided with one or two fly-wheels F⁶. In Fig. 3 two are shown, one attached to the crank-shaft 100 on one side of the engine and the other attached to the crank-shaft on the other side of the engine. The crank-shaft also carries means for communicating power, and in the present instance these means consist of the 105 pulley F¹⁰, fixed on and concentric with the crank-shaft F⁵ and shown in Fig. 3 at the left-hand fly-wheel F⁶.

The engine as thus far described may be either a horizontal or a vertical one. In the 110 present illustrative instance the engine is shown as vertical, because in this position it is best adapted to be located upon the carriage and combined therewith, as hereinafter described. 115

K is a bed-plate which carries the journal-bearings of the crank-shaft F⁵ and supports the upright pillars K' K' K' K', four in number, in turn respectively supporting the cylinder B and its enveloping shell A. In order 120 to more firmly support the said shell and cylinder in position, the upper end portions of each of the pillars K' is diminished in size, thereby forming a shoulder at K². The diminished portion K² of each pillar passes 125 through its adjacent flange projecting from the shell A and preferably integral therewith. The upper ends K³ of the said pillars are each screw-threaded, and a nut K⁵, screwed thereon, 130 clamps the shell A, with its cylinder B, firmly down upon the pillars K'. The bed-plate K rests upon and is fixed to the platform V of the vehicle. This platform rests upon a suitable framework. Such a framework is shown

in the drawings and consists of the side beams Z Z and end cross-beams Z Z.

Near the rear of the machine is an axle X, suitably journaled in bearings X' to the frame 5 of the platform of the vehicle, substantially as shown.

To the forward part of the vehicle is attached a tongue Y, provided with a double-tree Y', the tongue being pivotally connected 10 to the front axle by the branches or arms Y³ Y³. Of course when desired shafts or equivalent connections for enabling the vehicle to be drawn may be employed instead of the tongue Y.

15 Each terminal portion of each axle is provided with its wheel W, connected thereto in any suitable manner. The front axle X is at its center X² pivotally connected to the platform of the vehicle or to the running-gear 20 which supports the said platform in any of the well-known ways, as by a pivot or fifth-wheel or the like.

25 The wagon has four upright posts or supports S' S' S' S', two located near the bottom 25 of the platform and two near the rear thereof.

The preferred mode of securing these posts to the vehicle body or platform is as follows: A sleeve Z', provided with flanges Z² Z², is located against the outside of the beam 30 Z and secured thereto by screws or bolts passing through the flanges Z² and into or through the beam Z. There are four of these sleeves Z', two on one side of the vehicle and two on the other side of the vehicle, and in each of 35 them is set the foot of one of the posts S'. The flange Z² of each post prevents the latter from slipping down through its respective sleeve. At the forward end of the machine the cross-bar U³ extends between the forward 40 posts S' S' and is fixed thereto, and the rear end of the footboard U is connected to this cross-rod U³. A diagonal brace U' supports the forward end of each foot U, the rear end of the brace being fixed to the cross-rod U⁴, 45 extending between and fixed to the forward vertical posts S' S'. A brake is also present, arranged to bear against either the forward or rear wheels. In the present instance the brake operates against the rear edges of the rear 50 wheels and is constructed substantially as follows: A cross-rod T' is journaled in journal-bearings T², secured to the cross-beam Z, fixed to the under side of the rear end of the platform. To each end of this rod is fixed a brake-shoe T. The rod T' carries a lever T³, one end of 55 which is fixed at the point T⁴ to the rod T' and at the other end T⁵ to the longitudinal rod T⁶, which extends forward to the front end of the vehicle and is there pivotally connected 60 to the lever T⁸, pivoted at T¹² to the frame of the machine. The upper end of the lever may be provided with means for enabling it to be operated by the hand or foot. In the present instance a foot-plate T⁹, located on the 65 upper end of the said lever, enables the lever T⁸ and the brake to be operated by the foot of the driver.

A suitable seat is provided for the driver. In the present illustrative instance the seat L is supported in the following manner: On each post is located a projection L', and upon this projection is located a spring L², coiled around the post. Attached to the adjacent end of the seat is located a projection L³. As the driver sits upon the seat L the springs L² 70 are somewhat compressed and by their resiliency action render the vertical movements of the seat gentle while the wagon is passing over prominences and depressions in the roadway, whereby the wagon is subjected to vertical thrusts.

75 Supported upon the posts S' and secured thereto is a roof or top S², and through this roof and secured thereto is the wind-guard D²² D²³. This wind-guard is located directly over the igniter-chimney D⁷ D¹², and the function of this wind-guard is to carry the volatile products of combustion from the igniter up through the roof and away from the top of the vehicle and at the same time prevent 80 the wind from putting out the flame of the igniter.

85 The exhaust is provided with the vertical exhaust-pipe E', which leads into the muffler E², the latter passing through the roof S², substantially as shown. This muffler receives the carbonic-acid gas and muffles or deadens the harsh sound otherwise apparent when the exhaust abruptly terminates in the open air.

90 E³ indicates a cap on the roof, through which the chimney D²³ passes. This chimney conveys away the volatile products of combustion passing from the igniting apparatus. The upper end of this chimney is surrounded by a wind-guard or ventilator D²², 95 whereby the wind is prevented from affecting the combustion of the burner D⁴. In practice this chimney D²³ is slid down so as to cover the sphere D¹² and the upper end of the chimney D⁷, but in the drawings the chimney D²³ is shown raised to disclose the sphere D¹² and the upper end of the chimney D⁷.

95 R indicates the reservoir of gasolene for supplying the engine with hydrocarbon. This reservoir consists of the cylinder or receptacle R, secured to the roof of the vehicle S² by means of the supports or brackets R² R². The reservoir may be filled through an opening in its top, provided with a suitable stop R'. Through the lower portion of the reservoir extends an exit pipe or conduit R³ R⁵. A valve R⁴ is located in this exit-pipe preferably at the junction of the brackets R² R², and by this valve the amount of gasolene fed to the engine may be regulated. The pipe 100 or conduit R⁵ connects with the vertical conduit R⁶, and for the sake of compactness in construction and the protection of said conduit the latter passes down through one of the upright posts S' S' to the bottom of the 105 said post and there, as shown in Fig. 1, connects with the conduit R⁷. The main portion of the gasolene passes up through the conduits R⁸ and R¹⁰ to the carburetor C. The 110

amount of gasolene passing through these last-named conduits is regulated by the stop-cock R^9 , located between them. Also connected to the conduit R^7 is the conduit R^{12} , whereby gasolene is supplied to the burner D^4 of the igniter. The amount of gasolene thus fed to the burner D^4 is regulated by the stop-cock R^{13} . The top is preferably provided with suitable curtains, as S^8 , which may be lowered to protect the machinery from rain or snow.

The platform is suitably provided with a suitable step, as V' , connected to the platform by the braces V^2 V^3 . Below the platform and between the beams Z is located the water box or reservoir M . Connected to the interior space of this water-box is the supply-pipe N , whereby water from the said box is supplied to the water-space A' between the cylinder B and the shell A , and this water-jacket is present around the cylinder to keep it cool. The water is raised from the box M into the said space A' by means of the rotary pump P , rotated by means of the pulley-band P' , passing around the pulley P^2 of the shaft, on which is mounted the rotary piston of the said pump. This pulley-band P' passes around the pulley P^3 on the main shaft E and derives its power from the last-named pulley. Cool water from the water-box, supplied through the pipe N , preferably enters the space A' at the lower portion of the cylinder and flowing up through said space finds egress through the exit-pipe Q , which latter delivers the water by suitable means to the water-box M . In the present instance the exit-pipe Q delivers the water to the funnel Q' , which in turn conveys the water to the pipe Q , which in turn delivers it into the box M . Suitable means for filling the box M are shown in Fig. 3, where M' indicates the inlet-pipe, whose upper end is located at the upper side of the platform V and whose lower end is located in the interior space of the water-box. This inlet is preferably closed by a suitable cover, as M^4 .

In Figs. 8, 8', 8², 9, 9', and 9² is shown a suitable valve adapted to be used with carbureted air or with coal-gas, as the case may be. When the valve is used for carbureting the air, the conduit C' is connected with the carbureter, and the carbureted air enters the valve through said conduit C' and passes into the chamber n' . n is a valve closing the entrance to the chamber t , and C^2 the valve, hereinbefore mentioned, closing the entrance into chamber C^3 . Communication is made between the chambers C' , t , and C^3 when the valves are open. When the valves n and C^2 move back and when they are open, the carbureted air through chamber n' passes immediately through chamber t and into the chamber C^3 and thence into the cylinder, as aforementioned. When the valve is thus used for carbureting air, the tube m , opening into the chamber t , is closed, and when the valve is used for coal-gas the conduit m is connected

to the pipe through which the coal-gas is supplied to the engine, and the conduit C' , aforementioned, takes air and supplies it to the chamber n' . When the carbureter is on, this air can pass through the carbureter. When both gas and gasolene are to be used together in operating the engine, the pipe m will communicate with the gas-supply and gasolene will be furnished to the carbureter, the relative quantities of gasolene and gas being regulated, as desired.

When the valves n and C^2 are opened, the carbureted air and gas will commingle and pass through chamber C^3 , as aforementioned. When the valves n and C^2 are open, air is drawn through the conduit C' and chamber n' into the chamber t and gas is drawn through said conduit into chamber t , and the air and gas are there mixed and pass together into the chamber C^3 and thence into the cylinder.

While the various features of my invention are preferably employed together, one or more of the said features may be used without the remainder, and in so far as applicable one or more of the said features may be used in connection with gas-engines of a description other than the one herein specifically specified.

What I claim as new and of my invention, and desire to secure by Letters Patent, is—

1. In a gas-engine, the combination of a valve for admitting carbureted air and gas to the gas-cylinder, and an oscillatory rod C^6 pivotally connected to the stem C^4 of the said valve and substantially axially coincident with the said stem C^4 , and rod J laterally pivotally connected to rod C^6 and at substantially right angles thereto, and the governor for actuating said rod J and mechanism, substantially as described for actuating said valve, substantially as and for the purposes specified.

2. In a gas-engine, the combination of the compound valve having the valve n , and valve C^2 , chambers n' and t , the valves being on a common stem C^4 , and the latter pivotally united to a stem C^6 , connected to a stem J , operated by the governor, and stud G^3 elevated by reciprocating mechanism, and a spring C^7 , arranged on the stem C^4 , for depressing the compound valve when the latter is not elevated by stud G^3 , all in combination, substantially as and for the purposes specified.

3. In a gas-engine, the combination of the valve for supplying carbureted air or gas to the engine, and the igniter-valve, reciprocating lever G' carrying the stud G^3 , for engagement with the stem of the valve C^2 , and the hook or projection G^5 for engagement with the projection D^{17} of the valve-stem of the igniter-valve, and means substantially as described for returning the valves and their studs, substantially as and for the purposes specified.

4. In a gas-engine, the combination of the compound valve n and C^2 , chambers n' and t , valve-stem C^4 , stem C^6 , pivot uniting them, spring C^7 for depressing the valve, governor

and stem J, for moving the stem C⁶ laterally, igniter-valve, stem D¹⁴, and spring D¹⁵, for holding same closed, reciprocatory lever G', hook G⁵, thereof, projection D¹⁷ of stem D¹⁴, to be actuated by hook G⁵, and stud G³ for the actuation of stem C⁴ in opening the compound valve, substantially as and for the purposes specified.

5. In a gas-engine, the combination of the compound valve n and C², chambers n' and t, valve-stem C⁴, stem C⁶, pivot uniting them, spring C⁷ for depressing the valve, governor and stem J, for moving the stem C⁶ laterally, igniter-valve, stem D¹⁴, and spring D¹⁵, for holding same closed, reciprocatory lever G', hook G⁵ thereof, projection D¹⁷ of stem D¹⁴, to be actuated by hook G⁵, and stud G³ for the actuation of stem C⁴ in opening the compound valve, the projection D¹⁷, acting as the abutment for the upper end of the spring D¹⁵, and projection D¹⁶ being the lower abutment, substantially as and for the purposes specified.

6. In a gas-engine, the combination of the compound valve n and C², chambers n' and t, valve-stem C⁴, stem C⁶, pivot uniting them, spring C⁷ for depressing the valve, governor and stem J, for moving the stem C⁶ laterally, igniter-valve, stem D¹⁴, and spring D¹⁵, for holding same closed, reciprocatory lever G', hook G⁵, projection D¹⁷, means for rendering the projection D¹⁷ adjustable in relation to the length of the stem D¹⁴, substantially as and for the purposes specified.

7. In a gas-engine, the combination of the compound valve n and C², chambers n' and t, valve-stem C⁴, stem C⁶, pivot uniting them, spring C⁷ for depressing the valve, governor and stem J, for moving the stem C⁶ laterally,

igniter-valve, stem D¹⁴, and spring D¹⁵, for holding same closed, reciprocatory lever G', hook G⁵, projection D¹⁷, means for rendering the projection D¹⁷ adjustable in relation to the length of the stem D¹⁴, and projection D¹⁶, between which and projection D¹⁷ is located spring D¹⁵, substantially as and for the purposes specified.

8. In a gas-engine, the combination of the compound valve having the valve n, and valve C², chambers n' and t, the valves being on a common stem C⁴, and the latter pivotally united to a stem C⁶, connected to a stem J, operated by the governor, and stud G³ elevated by reciprocatory mechanism, and a spring C⁷, arranged on the stem C⁴, for depressing the compound valve when the latter is not elevated by stud G³, the stem C⁴, being compound and united by screw connections, for imparting to it capacity to be lengthened and shortened, substantially as and for the purposes specified.

9. The combination of the valve, stem C⁴, compound and united by a screw connection for rendering it capable of being lengthened or shortened, spring C⁷ for holding valve down, pivoted stem C⁶, governor and means for enabling the latter to move the stem to one side, lever G', stud G³ thereof, for contact with stud C⁶, and projection G⁵ thereof, igniter-valve, stem D¹⁴, abutment D¹⁶, and spring D¹⁵, and projection D¹⁷, D¹⁸, adjustable, for the stem D¹⁴, and for contact with projection G⁵, substantially as and for the purposes specified.

BENJAMIN C. VANDUZEN.
